UNITED STATES PATENT OFFICE.

GEORGE KESSELRING, OF READING, MICHIGAN.

WHEEL-HUB.

SPECIFICATION forming part of Letters Patent No. 710,984, dated October 14, 1902.

Application filed April 17, 1902. Serial No. 103,343. (No model.)

To all whom it may concern:

Be it known that I, GEORGE KESSELRING, a citizen of the United States, residing at Reading, in the county of Hillsdale and State of Michigan, have invented a new and useful 5 Wheel and Hub, of which the following is a specification.

This invention relates generally to wheels, and more particularly to an improved 10 construction of hub.

The object of the invention is to provide a cheap and simple and at the same time strong and durable construction of hub, one which can be used in connection with the ordinary 15 spoke-wheel or with a wheel of the solid or block pattern.

With these objects in view the invention consists in the novel features of construction, 20 all of which will be fully described herein-
after and pointed out in the claims.

In the drawings, Figure 1 is a side elevation of a wheel constructed in accordance with my invention, a portion of the hub being shown in section. Fig. 2 is a detail section 25 view of the hub. Fig. 3 is a perspective view illustrating the sections of the hub detached or disconnected.

In constructing a hub in accordance with my invention I employ the outer section A, 30 the inner section B, and the central or connecting-section C. The sections A and B are formed with tapering bores A' and B', through which the axle-skein is passed, while the bore of the central section C is made straight and of 35 a diameter greater than the bore of the hub-
sections, so that the said central section forms only a connection, but does not form a bearing for the axle-skein. The sections A and B are formed with internally-threaded por- 40 tions A² and B², respectively, and the central section C is threaded externally upon both ends with a right-hand thread, as shown at C², so that the sections A and B can be se-
curely connected through the medium of the 45 sections C. The sections A and B are also formed with annular flanges A³ and B³, be-
tween which the spokes D are secured by means of the bolts D'. As before stated, my

improved construction of hub can be used in connection with a spoke-wheel such as 50 shown in Fig. 1; but it will of course be understood that the hub can be used equally as well with the solid or block pattern of wheel, the segments of wood forming the wheel be-
ing secured between the flanges A³ and B³ by 55 means of bolts D'.

The simplicity of the device enables me to construct the hub in an exceedingly cheap and durable manner, and another advantage of its simplicity is that it does not require a 60 skilled mechanic to assemble the parts or to disconnect them when either operation be-
comes necessary.

Having thus fully described my invention, what I claim as new, and desire to secure by 65 Letters Patent, is—

1. A wheel-hub comprising outer and inner sections each having an outwardly-extending flange formed at their inner ends and a tapering bore, the inner ends of said sections 70 being laterally recessed and threaded interiorly of the flanged portion, and a central section having a bore of larger diameter than the bores of the outer sections and exteriorly threaded at the ends, said threaded portions 75 being adapted to engage the threaded re-
cessed portions of the outer sections.

2. A wheel-hub comprising outer and inner sections each having an annular flange sur- 80 rounding its inner end, said sections being interiorly recessed and threaded at the inner end, and having a tapering bore extending from said threaded portion to the outer end said bore being of a smaller diameter than the threaded portion whereby an interior 85 shoulder is formed, an inner section similar to but oppositely formed, and a central sec-
tion having an interior diameter greater than the bores of the outer and inner sections, said central section being threaded adjacent its 90 ends and adapted to rest against the shoul-
ders formed in the other sections.

3. A hub comprising the inner and outer sections having tapered bores, the opposing ends of said sections having internally- 95 threaded portions, a central connecting sec-

tion threaded externally upon opposite ends arranged between the said inner and outer sections, and connected to the threaded portions, the bore of said central section being straight, and of a greater diameter than the tapered bore of either section, and the outwardly-projecting annular flanges integral

with the inner and outer sections and between which the spokes are secured, substantially as specified.

GEORGE KESSELRING.
